UNITED STATES PATENT OFFICE.

ALEXANDER ARCHIPENKO, OF NEW YORK, N. Y.

APPARATUS FOR DISPLAYING CHANGEABLE PICTURES.

Application filed June 2, 1925. Serial No. 34,432.

My invention relates to changeable picture devices and more particularly to a mechanical motion picture or changeable picture-device of the general type in which the effect is produced by movement of portions of the picture-plane surface or in which portions of the picture are changed, which portions consist respectively of narrow portions of different belts or aprons mounted 10 for movement in fixed locations in the picture plane.

This apparatus is peculiarly adapted to displaying the decorated belt units prepared in accordance with the method of decorating 15 described in my application Serial No. 45,435 filed July 22, 1925.

The apparatus of the present invention may be used for operating the belts while 20 they are being decorated or for later displaying the same or other previously decorated belts.

The improvements are designed primarily 25 for displaying a single picture or scene in such a manner as to suggest life and movement, the phases of the picture or scene changing gradually so as to merge, fade or develop into one another in a smooth and natural manner. The resultant pictures are 30 peculiar in that one characteristic of them is a tendency to provide an optical illusion effect, possibly due to the fact that the display field does not move as a whole, but in fact the surfaces comprising the field are so small that no movement is noticeable unless the observer is very close to the machine.

The method of decoration requires as a 35 fundamental some apparatus of the type hereinafter particularly described and which may be briefly classed as that in which a surface to be either decorated or displayed is made up of a large number of relatively narrow surfaces, preferably quite flat, and the assembly of the narrow surfaces providing a substantially plane surface. The 40 narrow surfaces are respectively portions of long belts grouped together and so mounted as to display only a restricted portion thereof at any one time.

Another peculiarity of this structure is 50 that no one belt will receive a picture complete in itself, assuming that a belt might be withdrawn from the machine and displayed in its extended form. It is also pe-

culiar for the reason that the method requires the use of an assembly of surfaces. 55 The belts cannot be decorated separately apart from the assembly and then assembled although theoretically possible, it is not practical.

One important object of the invention is 60 to provide an apparatus of the above type in which the movable elements of the picture-plane surface may be maintained in contact to present a continuous surface without rubbing and consequent wear between the 65 said movable elements.

Another object is to arrange the complete 70 set of picture-plane elements in a separable unit capable of being removed from or placed in the remainder of the apparatus 75 without disturbing the proper registering and working relation between the movable picture-plane elements, and without dismounting or disorganizing the driving mechanism, thus rendering such complete 75 sets or display units interchangeable and capable of being interchanged by persons unskilled in the handling of machinery.

A further object is to provide interchangeable units of the above type that may be 80 collapsed or reduced in bulk in such manner that the operative adjustments of the parts will be preserved and the unit will be substantially self-braced and protected against 85 injury in shipment.

The above and additional features and 90 details of my invention will be described and claimed in the following specification and claims, and illustrated in the accompanying drawings, in which:

Figure 1 is a side elevation of the complete changeable picture device, partly in section;

Figure 2 is a front elevation;

Figure 3 is an enlarged detail view of the 95 reversing mechanism;

Figure 4 is a side view of Figure 3 partly in section;

Figure 5 is a detail view of the reversing 100 lever;

Figure 6 is a plan view of the display unit with the immediately associated elements of the machine, on a reduced scale;

Figure 7 is a perspective view of a display unit removed from the machine, partly 105 in section; and

Figure 8 is a perspective view, on a much reduced scale, of a display unit folded for storage or shipment.

Figure 9 is a perspective view of a mechanism for providing intermittent motion, as an alternative to the continuous drive mechanism shown in Figures 1 and 2.

Referring to the drawings in detail, and first to Figures 1 to 5, the base on which the various parts are mounted is indicated at 1. On this base is mounted a driving motor 2 illustrated as an electric motor and which may be controlled by any suitable switch or other means, not illustrated. The driving shaft 3 is coupled through pinion 4 and gear 5 with a counter shaft 6 which carries a bevel gear 7. This bevel gear 7 meshes with a pair of oppositely arranged bevel gears 8 and 9, loosely or rotatably mounted on the shaft 10 (Figures 3 and 4) so as to be turned thereon in opposite directions by the gear 7, the shaft 10 having bearings in the frame 11. The gears 8 and 9 are provided with clutch faces 12 and 13, respectively, complementary to the clutch faces 14 and 15 of a double face sliding clutch member 16 splined on the shaft 10 and provided with an annular or circumferential groove 17 engaged by a shifting yoke or fork 18 for sliding the movable clutch member into and out of engagement with the complementary clutch faces on the oppositely rotating gears 8, 9. To secure a straight line movement of the fork 18 along the axis of the shaft 10, the fork is mounted on a straight carriage or plate 19 slidably mounted in notches in the front edges of the side portions of frame 11, as indicated in Figure 4, and held therein by flat bearing caps 20, 21. Reciprocating movement of the plate 19 is effected through a pin 22 mounted thereon and arranged to be engaged by a fork 23 at the lower end of a lever 24 pivoted at 25 on the shaft 26 mounted in the frame 27. The upper portion of the lever 24 is in the form of a transverse frame made rigid by a cylindrical bearing 28 on the shaft 26 and a transverse brace rod 29.

To insure a quick or snap movement of the lever 24 and give an off-center bias thereto, a roller 30 is slidably mounted thereon above the pivot 25 by means of a carriage 31 and slot 32, and made to constantly bear downward on the stationary cam 33, formed on the upper portion of frame 27, under tension of the retractile springs 34, connected between the carriage 31 and the lower or forked end of the lever 24. Thus, when the upper part of the lever 24 is moved slightly to either side of the central position shown in Figure 3, the roller 31 passing to one side of the central crest of the cam 33 will ride down into one or the other of the depressions of the cam under tension of the retrac-

tile springs and rock the lever on the pivot 25 swinging the fork 23 into engagement with the pin 22 and sliding the plate 19. A given amount of lost motion is allowed between the arms of the fork 23 and pin 22 to prevent movement of the plate 19 during movement of the roller from one extreme side or cam depression to the central crest. As the clutch member 16 is splined on the shaft 10 this shaft is caused to rotate with one of the two oppositely driven bevel gears 8 or 9 according to the direction in which the clutch is thrown.

Motion is transmitted from the shaft 10 through the bevel gears 35 and 36 carried at its ends, and bevel gears 37 and 38 to the vertical shafts 39 and 40, respectively, the gears 37 and 38 being fixed to their respective shafts and so positioned thereon in relation to the driving gears 35 and 36 as to cause the shafts 39 and 40 to always move in the same direction. The vertical shafts 39 and 40 transmit motion to four screw-feed shafts, two of which are indicated at 41 and 42 in Figure 1, the other two, not shown, being similarly disposed on the other side of the machine. Motion is transmitted from the shaft 40 (Figures 1 and 2) to the screw shafts 41 and 42 through the pairs of bevel gears 43, 44 and 45, 46, respectively. Similarly, motion is transmitted to the upper and lower screw shafts on the other side of the machine through the pairs of gears 47, 48 and 49, 50.

A set of four horizontal rails 51, 52, 53 and 54 (Figures 1 and 2) extend from front to rear of the machine supported on the frame members 55, 56, 57, 58 (Figure 2), in front, and 59, 60 (Figure 1) and others similarly positioned on the opposite side, in the rear, the upper frame members being supported on four large vertical angle beams or columns, of which three are shown, 61, 62 and 63.

A movable frame 64 is mounted on the four rails 51 to 54, engaging the top rails through notches in the pair of blocks 65-66 carried on the upper corners of the movable frame, and resting on the lower rails through rollers 67-68 journaled in the pair of blocks 69-70 fixed to the lower corners of the movable frame. The four blocks 65, 66, 69 and 70 are provided with openings in threaded engagement with the feed-screw shafts, so that rotation of all four screw shafts in the same direction will drive the movable frame 64 along the rails forward or backward of the machine, according to the direction of rotation.

To reverse the direction of travel of the frame 64 at predetermined limits of travel, the frame in its movement is caused to actuate the reversing clutch lever 24 through a tripping bracket 71 (Figures 2, 3, and 4) and a bell-crank lever 72 which is mounted on a supporting post 72a. The bell crank

lever 72 has its central or stationary pivot at 78 on the post 72*, while one arm is pivoted to the frame 64 at 74 and the other arm pivoted to the tripping bracket 71 at 75.

5 The tripping bracket 71 is slidably mounted on the flat bar 76 fixed to the frame members 55 and 56 (Figure 2), and carries a pair of upstanding posts 77—78 arranged, as shown in Figures 3 and 4, to engage with the top 10 horizontal or cross member of the lever 24 and trip the same in the sliding movement of the tripping bracket, the posts 77—78 being adjustably mounted to permit variation of the spacing between them for timing the 15 tripping of the lever 24. Pivots 74 and 75 are respectively in slots 74^a and 75^a.

To avoid making the rear arm of the bell-crank lever sufficiently long to follow the entire movement of the movable frame, it may 20 be actuated thereby through any suitable lost motion connection such as a chain (not shown), or elongated slot and pin connection (as shown in Figure 5) arranged to communicate motion of the frame to the 25 lever when the frame is near one of its limits of travel only.

The apparatus above described constitutes the driving mechanism of the system. Before proceeding to a detailed description of 30 the display unit and its operation, the operation of the driving mechanism in producing a reciprocating motion of the display actuating frame 64 will be briefly described.

Operation of driving mechanism: The 35 motor 2 being put into operation, motion is transmitted from the motor shaft 3 through gears 4, 5 and shaft 6 to bevel gear 7 rotating it constantly in a clockwise direction, as viewed in Figure 2, which in turn rotates 40 the loose bevel gears 8 and 9 in opposite directions. The clutch member 16 being in the position shown in Figure 2, in engagement with the clutch face on wheel 9, motion is transmitted from 9 to the shaft 10 45 from which motion is transmitted through gears 35—37 and 36—38 to shafts 39 and 40 and from them to the four screw shafts 41, 42, etc. by way of the four sets of bevel gears 43—44, 45—46, 47—48 and 49—50, the various gears and shafts turning in the direction indicated by the adjacent arrows. This 50 causes the movable frame 64 to move forwardly of the machine transmitting motion through the bell-crank lever 72 to the tripping bracket 71 to move it toward the right as the frame 64 moves forward until the frame 64 arrives at its forward limit, predetermined by the setting of the posts 77—78, when the post 77 striking the lever 24 will trip it to the right (Figure 2), causing the clutch member 16 to move out of engagement with the clutch member on gear 9 and into engagement with that of gear 8. This reverses the motion of the screw shafts 55 causing the movable frame 64 to move to-

ward the rear of the machine. Motion is now transmitted from the frame 64 through bell-crank lever 72 to the tripping bracket 71 to move it toward the left in Figure 2 until the frame 64 reaches the rearward limit of 70 its travel as determined by the setting of post 78, whereupon the clutch lever 24 is engaged by the post 78 and tripped to the left, reversing the motion of the machine. This completes the cycle of operations which may 75 be repeated indefinitely.

Referring now to the display unit, this is shown in operative connection with the driving mechanism, Figure 1, where it is indicated as a whole by the reference numeral 80 79, and is shown removed from the machine in Figures 7 and 8. It consists essentially of an arrangement for presenting a display surface or picture plane 80, composed of movable surface elements 81, in the form of 85 narrow strips juxtaposed one above the other, to form a continuous plane surface and constituted of portions of different belts or aprons 82 movable into and out of the picture plane, the movement being accomplished by the driving mechanism above described. The height of the display portions 90 81 of each strip may vary from less than one inch to greater than one inch depending on the size of the entire surface, the type 95 of illustration and the ultimate effect to be conveyed. In one installation the strips were about three quarters of one inch in height and about one hundred were used in the assembly.

In the practical embodiment here shown, the aprons 82 are illustrated as in substantially continuous loops held in place in the two frames 83—84 by spaced platens 85 over which they pass, the platens being mounted 100 in the frames on cubes 86 at each end, which cubes are secured to the flat bars 87 fixed in the frames. The aprons 82 actually are not woven as continuous bands but are each 105 single strips looped back and having opposite ends abutting as at 94 in Fig. 6 and both held by common fastening means and thus the expression "endless" is used to express the idea that the aprons are substantially continuous. As shown, the platens 85 are in the form of angle beams with beveled edges to prevent wear of the aprons 82 and reduce friction, and so spaced by proper 110 spacing of the blocks 86 as to bring the aprons passing therebetween in contact with each other to present a solid front where they pass over the outer faces of the platens 85. Because of the contact between adjacent apron surfaces, it is important that 115 there be no relative movement between such surfaces to produce rubbing or wear which would result in marring of the picture portions. To prevent any such relative movement, means are provided for positively and 120 directly moving all the aprons in unison.

This consists of a middle channel frame built up of angle members 88-89 carrying a series of cross beams 90, preferably of wood, to each of which adjacent portions of a pair of aprons are secured by means of clamping plates 91, fastened by screws 92. Turned up end portions 93 of the clamping plates are positioned in the channel of the frame 88-89 and serve as spacer elements 10 to properly space the beams 90 with which the plates 91 are coextensive, as indicated in Figure 7. The plates 91 also may serve as means for joining the ends of the apron loops by clamping them, as indicated in 15 dotted lines at 94 in Figure 6. The beams 90 and plates 91 are held in the channel frame 88-89 securely and firmly, especially against lost-motion in a horizontal direction so as to form a unitary or common, direct, 20 rigid connection between all the aprons, resulting in movement of all the aprons in unison.

The display unit 79 rests in the machine on a pair of longitudinal beams 95, with the 25 front and rear upright beams 61, 62, etc. of the machine by means of cleats 96. Figures 1, 2 and 6, pivoted on the angle beams 61, 62, etc., and arranged to be turned down across the vertical sides of the frames of 30 the display unit as shown in Figure 6, the pivots of the cleats being relieved of strain by bayonet shaped limit stop bars 97 riveted or otherwise secured to the angle beams 61, 62, etc. To properly tension the aprons 82, 35 tensioning screws 82 are arranged in the frames 83 and 84 in threaded engagement therewith, and positioned to bear against the cleats 96.

As indicated in Figure 6, the middle 40 frame 88-89 of the display unit is fastened to the movable frame 64 of the driving mechanism by means of the screws 98 (Figures 1, 2 and 6).

Operation of display unit: With the parts 45 connected as above described and the driving mechanism set in operation to reciprocate the movable frame 64, as previously described, the middle frame 88-89 of the display unit will be reciprocated between the front and rear frames thereof, moving 50 with it the portions of the apron loops 82 fastened to the cross beams 90 while the unattached portions move in the opposite direction. The aprons are thus caused to move over the platens 85 through the picture plane, alternate aprons moving in the 55 same direction and adjacent portions in opposite directions, as indicated by the arrows in Figure 2. As the adjacent apron portions remain in contact during their movement into and out of the picture plane 80, the exposed portions of the aprons present a solid or continuous surface made up of strip elements 81. Upon each complete 60 change of elements 81 there is a complete

change of the whole surface, so that any picture or other decoration thereon will give place to such different picture or other phase of the same as may exist on the succeeding surface constituted of the succeeding strip elements. Thus, changeable views or motion picture effects may be produced and without high speed travel of the aprons, as it is only necessary for the aprons to travel a distance equal to the width of one picture plane element in order to make a 75 complete change of view over the whole picture plane. Also, as the change in elements is gradual or continuous, the transition of view may be made continuous, resulting in a more complete illusion of motion in the picture.

To substitute a new display unit for the one in use, the cleats 96 are turned up to 80 release the end frames 83 and 84, and the middle frame 88-89 by disengaging the screws 98 therefrom, and the whole display unit withdrawn through the back of the machine, right hand side of Figure 1, the frames 83, 88-89 and 84 resting and sliding on the longitudinal beams 95. After the display unit is removed it will remain intact with the operative relation of the several parts retained as indicated in Figure 7. To reduce bulk and protect the aprons 82 from exposure and mechanical injury during storage or shipment, the unit may be collapsed and made substantially self protecting with the addition of a few extra brace members 99, as shown in Figure 8.

To install the new display unit it is slid in on the beams 95 from the rear right hand side of Figure 1, the front and rear frames, 83-84 fastened in place and adjusted to 105 properly tension the picture aprons, and the middle frame 88-89 secured to the movable frame 64 of the driving mechanism, all as previously described. Thus, it will be seen that the entire display may be changed without disconnection or any alteration of the driving mechanism, so that such change may be readily made by any one, without special knowledge or skill in the handling of machinery.

Where it is desirable to produce an intermittent motion of the aprons of the picture unit, the intermittent transmission mechanism shown in Figure 9 may be used for transmitting motion from the motor 2 to the bevel gear 7 (Figures 1 and 2) in substitution of that shown in Figures 1 and 2. This consists of a counter shaft 101 driven from the motor shaft 3 through the worm gear connection 102-103 and in turn driving a clutch gear 104 through a pinion 105. The clutch gear 104 is loosely mounted on the fixed shaft 106 and carries a triangular clutch dog 107 pivoted thereto at 108. The lower arm of the dog 107 is provided with 110

70

80

a roller 109 arranged to engage with a lifting cam 110 formed on a cam plate 111 adjustably mounted on the base 112 by means of bolts 113 and arc shaped slots 114 for 5 rotary adjustment about the fixed shaft 106. An intermittent gear wheel 115 is rotatably mounted on the fixed shaft 106 above the clutch gear 104 and meshes with a pinion 116 fixed to the counter shaft 117. The gears 10 104 and 115 are supported in proper spaced relation on the fixed shaft 106 by suitable spacing collars 118, 119 and 120, fixed to the shaft. The gear wheel 115 is provided with rollers 121 mounted within and to one 15 side of the openings 122 and positioned to be engaged by the nose 123 of the clutch dog 107, as shown in the drawing. To prevent backward movement of the gears 115, that is, movement counter to the direction 20 indicated by the adjacent arrows, it is provided with detent recesses 124 arranged to be engaged by a pawl 125 pivoted on the fixed collar 120. Motion is transmitted from the counter shaft 117 through bevel gears 25 126—127 to counter shaft 128 and from thence through gears 129—130 and shaft 131 to bevel gear 7 which is the same as the bevel gear 7 in the other figures previously described.

30 Operation of intermittent motion mechanism: Starting with the parts in the position shown in Figure 9, and with the motor shaft 3 rotating in a direction to drive the gear 103 in the direction indicated by the adjacent arrow, the counter shaft 101 and clutch gear 104 will be rotated in the directions indicated by the arrows, the clutch gear 104 carrying the dog 107 around with it, which in turn moves the wheel 115 35 around, in the direction indicated by the arrow, by engagement of the nose 123 of the dog 107 with the roller 121, the dog 107 being held by engagement of the cam 110 with roller 109. The gear 115 is thus moved 40 around with the clutch gear 104 until the dog rides off the cam 110 at the right end, whereupon the dog drops down entirely out of the opening 22 and clear of the wheel 115, which then stops, while the wheel 104 and 45 dog 107 pass on in their rotation about the fixed shaft. The parts are so proportioned and spaced or timed in relation to each other that when the nose 123 of the dog drops out of engagement with the roller 121, the pawl 50 125 drops into one of the detents 124, locking the gear 115 against backward movement. The wheel 104 and dog 107 continuing their rotation, bring the roller 109 into engagement with the cam 110 from the left 55 and the roller riding up on the cam lifts the nose 123 of the dog 107 into engagement with the next succeeding roller 121, brought into position for such engagement 60 by the previous movement of the gear 115. 65 The cycle of operations just described is re-

peated indefinitely, causing an intermittent movement of the gear 115 around the shaft 106, which is transmitted through the transmission elements 116, 117, 126, 127, 128, 129, 130 and 131 to the bevel gear 7 of the 70 display actuating mechanism of Figures 1 to 5 previously described. By suitable proportioning of the length of the cam 110 and selection of the number of rollers 121 or other cams similar to cam 110, the number 75 or frequency of the intermittent movements, as well as the relative duration of periods of movement and rest, may be varied.

With the apparatus of this invention, a 80 complete picture may be displayed at all times.

Two types of motion may be used in displaying the decorated surface; first, a 85 smooth and continuous motion, which discloses a slow development in the picture, but constantly with a complete picture in view; and second, a regular step by step or periodic motion. Pictures and decorations made in accordance with the method described in my copending application, Serial No. 45,435, 90 filed July 22, 1925 will always display a complete picture regardless as to speed of machine or smoothness or intermittency of motion. For a series of non-continuous pictures there should be a conformity between 95 the subject matter, either decoration or text, of the display surface and the intervals produced by the motion of the machine.

Heretofore, changeable picture apparatus 100 has been known in which there were a plurality of belts carrying illustrations and assembled to display an effect on a plane surface made up of a plurality of smaller portions. On such apparatus, decorated belts 105 have been used, the belts being placed in a machine and operated as nearly in harmony as the operation of the machine permitted. This latter has been done when a series of disconnected pictures have been placed on bands and shown in intermittent operation. 110 Also, photographic operations have been conducted with apparatus using a plurality of belts in which the belt material was either a film or other sensitized surface. A step by step movement, such as provided by a 115 Geneva gear or motion picture gearing was necessary in such arrangements in order to take pictures or to reproduce the same, inasmuch as a complete new portion of the sensitized surface must be provided for each picture or else portions of the surface would bear overlapping pictures. Contrasted to such prior inventions, the present invention relates to apparatus for displaying painted bands or belts of the decorating system as 120 result of which new effects are produced to the eye when the resultant surface is displayed and a complete picture is constantly 125 in view, even if the bands are moved for a distance less than the width of the exposed 130

strip or portion of the band. Also in contrast to such prior uses, the present adjacent belt structures are in close contact immediately at the plane of the picture and there is no space between the adjacent narrow portions of the bands on the display surface, whereas in prior display apparatus, it has been customary to allow some space between adjacent bands, the need for such space being due possibly to the different directional movements of the belts or bands.

Quickly dried colors are used in decorating the belts, and the colors are thinly spread.

Emphasis is placed on the direction of movement of adjacent portions of each set of two belts. If the belts were photographic films or carried on some type of surface other than painted surfaces, possibly the direction of movement might not be particularly important. However, for painted surfaces of the type produced by the present method, it is necessary that the belt movements be at the same rate of speed and in the same direction for contacting belt portions.

The apparatus lends itself readily to installation in display windows where it may be suitably enclosed to show only the picture surfaces, or the apparatus may be provided with a casing or housing sufficient to enclose the machinery and reveal only the display surfaces. The apparatus may be adapted to use in any size and shape, and for advertising, exhibition, artistic and educational purposes.

While I have herein shown and described certain specific embodiments of my invention, for the purpose of disclosure, it is to be understood that the invention is not limited in its scope to such specific embodiments, but contemplates all such variants and modifications thereof as fall within the scope of the appended claims.

I claim:

1. In a changeable picture display system, the combination with a supporting frame and driving mechanism therefor, of an interchangeable display unit comprising a plurality of movable aprons and guide supports therefor arranged to guide the aprons a portion at a time through a common picture plane, each apron having a support at the picture plane and one at the opposite end of the apron, and actuating means directly engaging said aprons for moving the same and located intermediate the length thereof, said guide supports being arranged to be mounted in said supporting frame and said actuating means being arranged to be coupled to said driving mechanism for transmitting motion from said mechanism to said movable aprons.

2. In a changeable picture system, the combination with an exhibiting machine and a driving element therefor, of an interchangeable

display unit comprising a plurality of movable aprons and supporting means therefor arranged to support said aprons in a position to move through a common picture plane, and a bodily movable rigid element connected to each of said aprons for uniformly moving all of the same, said unit being arranged to be mounted in said exhibiting machine with said rigid element in operative relation to said driving element for transmitting motion therefrom to all of said aprons in unison.

3. In a changeable picture display system, the combination with a frame and a movable element with driving mechanism therefor, of an interchangeable display unit comprising a support arranged to be connected to said frame and carrying a plurality of aprons arranged to be moved through a common picture plane, and bodily movable rigid connecting means directly fastened to each apron and arranged to be connected to said movable element for transmitting motion therefrom to said aprons when bodily moved.

4. In a changeable picture device, a display unit comprising a plurality of picture aprons arranged to have portions thereof moved into and out of a common picture plane to constitute changeable portions thereof and having means for holding the aprons in proper coordinated relation and rigid bodily movable means engaging all of said aprons for simultaneous movement thereof, in combination with supporting means for supporting said display unit in operative position and driving means arranged to be connected to said apron engaging means.

5. A changeable picture display system comprising actuating mechanism together with interchangeable display units, each unit comprising a plurality of aprons arranged to be moved through a common picture plane in unison, and a rigid bodily movable element connected to a plurality of said aprons and arranged to be connected with said actuating mechanism for moving said aprons in unison.

6. A changeable picture device comprising a display surface or picture plane made up of a plurality of surface elements in the form of narrow strips arranged side by side and in contact with each other at the side margins to give the appearance of a solid front and contacting portions being arranged to move together in the same direction and at the same speed, said surface elements being constituted of portions of a plurality of different movable aprons arranged to be moved to change the portions constituting the surface elements, an individual supporting guide for each surface element and located at said front and over which guides said surface elements are

adapted to move, and a rear set of supporting guides, one for each apron, spaced from said guides of said front and on which said aprons are supported, adjacent aprons being in contact with each other between the adjacent guides of said front.

7. In a changeable picture apparatus, a display unit consisting of a plurality of looped aprons, each of the same length, two 10 guide platens spaced apart and one positioned at each end of each loop and extending transversely through the loop and adapted to support the opposite ends of the loops when the latter are stretched taut, and a 15 common rigid fastening element located between spaced platens and secured to each of said aprons, whereby when said fastening element is bodily moved, all aprons move with it at the same rate of speed.

20 8. In a changeable picture apparatus, a display unit consisting of two oppositely faced fronts spaced apart, a plurality of guide platens in each front and parallel to each other, a plurality of looped aprons each 25 one extending over opposite platens of both oppositely faced fronts and extending between said platens as a substantially continuous belt, and a common rigid fastening element located between said fronts and secured to each of said aprons and bodily movable, whereby when said fastening element is moved all of said aprons move with it at the same rate of speed sliding over the platens of both fronts according as the fastening 35 element moves.

9. In a changeable picture apparatus, the combination with a supporting frame and driving mechanism mounted therewith, of an interchangeable display unit consisting 40 of two oppositely faced fronts spaced apart, a plurality of guide platens in each front and parallel to each other, a plurality of looped aprons each one extending over opposite platens of both oppositely faced fronts 45 and extending between said platens as a substantially continuous belt, and a common rigid fastening element located between said fronts and secured to each of said aprons and bodily movable, whereby when said fastening element is moved all of said aprons move with it at the same rate of speed sliding over the platens of both fronts according as the fastening element moves, said unit being collapsible when removed from 50 said supporting frame, and means for coupling said opposite fronts to said supporting frame to tension said aprons and draw them taut between the said platens.

10. In a changeable picture device, a display unit comprising a plurality of aprons each looped over a pair of front and rear platens, said front and rear platens being supported in front and rear frames respectively and arranged to present the looped 65 end portions of the aprons in a common

plane in front and rear planes respectively, and an intermediate bodily movable substantially rigid element directly engaging each of said aprons whereby movement of all aprons is at the same rate of speed.

70 11. In a changeable picture device, a display unit comprising a front frame and a rear frame spaced apart, a plurality of platens mounted side by side in each frame, a plurality of movable aprons looped one over each of a front and a rear platen, said platens being held in said frames at such a distance apart as to cause adjacent of said aprons to contact with each other in passing therebetween, a bodily movable intermediate frame encircling said aprons, cross beams connected across said intermediate frame through the apron loops, each beam being fastened to the adjacent members of a pair of loops for moving adjacent pairs in unison.

75 12. In a changeable picture device, a picture plane made up of a plurality of elements arranged to have portions thereof moved into and out of the picture plane, and a unitary bodily movable actuating element directly engaging all of said elements removing all of them in unison.

80 13. In a display device having a plurality of aprons arranged one above the other to be moved in unison, means for transmitting motion to said aprons comprising a bodily movable frame encircling the aprons and rigid beams carried by said frame and fastened one to each of adjacent aprons.

85 14. In a changeable picture device, a display unit comprising a front frame and a rear frame, a plurality of platens mounted side-by-side in each frame, a plurality of movable aprons each looped over a pair of platens, one a front platen and the other a rear platen, a bodily movable intermediate frame surrounding said aprons, cross beams mounted in said intermediate frame, each beam connected to and connecting the four ends of a pair of aprons to complete two 100 loops and connect them for direct movement by the intermediate frame.

105 15. In a changeable picture device, a plurality of looped aprons arranged in a pile of elongated loops with the ends of the loops presented in a common plane and arranged to move to change the surface of the plane, said loops being formed in connected pairs, each pair comprising a pair of apron strips having their four ends fastened together, and a common transverse bodily movable actuating beam, extending across the strips and to which the four ends are secured for moving the pair in unison.

115 16. A changeable picture device comprising a picture plane made up of surface elements constituted of portions of movable aprons, bodily movably unitary action transmitting means fastened directly to all the aprons, and driving mechanism detachably 120 125 130 135

connected with said motion transmitting means, whereby the latter may be moved to effect corresponding movement of all said aprons.

5 17. A changeable picture device comprising a picture plane made up of surface elements constituted of portions of movable aprons, bodily movable unitary motion transmitting means fastened directly to all 10 of said aprons and having a limited oscillatory movement, and driving mechanism detachably connected with said motion transmitting means, and means operable upon a predetermined extent of movement of said transmitting means to reverse the direction of movement of said driving mechanism.

15 18. A changeable picture device comprising a picture plane made up of surface elements constituted of portions of movable

20 aprons, bodily movable unitary motion transmitting means fastened directly to all said aprons and having a limited oscillatory movement, driving mechanism detachably connected with said motion transmitting 25 means, and means for intermittently operating said driving mechanism, and means for reversing the direction of movement of said driving mechanism at predetermined 30 positions of said transmitting means.

35 19. A changeable picture device comprising a picture plane made up of surface elements constituted of portions of movable aprons, bodily movable unitary motion transmitting means fastened directly to all 40 said aprons and having a limited oscillatory movement, driving mechanism detachably connected with said motion transmitting means, together with means for intermittently operating said driving mechanism.

45 20. A changeable picture device comprising a picture plane made up of surface elements constituted of portions of movable aprons, bodily movable motion transmitting means fastened directly to all said aprons, and having a limited oscillatory movement, and driving mechanism detachably connected to said motion transmitting means combined with means operable upon a predetermined extent of movement of said transmitting means to reverse the direction of movement of said driving mechanism, and means for variably adjusting the points of reversal.

50 21. In a changeable picture apparatus, a display unit comprising a plurality of dec-

orated looped aprons arranged face to face and with opposite ends of each apron extending toward each other, each apron being of the same length, and common securing means holding the opposite ends of each 60 apron, two guide platens in each looped apron and spaced apart and one positioned at each end of each loop and adapted to support the opposite ends of said loops when the latter are stretched taut, the end portions at one end of said plurality of aprons being in a first common plane, constituting a first display surface, and the opposite end portions being in a different and second plane and constituting a second display surface, and means for moving said decorated looped aprons over said platens to change the picture displayed in each plane display surface.

55 22. In a changeable picture apparatus, a display unit comprising a plurality of decorated looped aprons arranged face to face and with opposite ends of each apron extending toward each other, two guide platens in each looped apron and spaced apart and 65 one positioned at each end of each loop and adapted to support the opposite ends of said loops when the latter are stretched taut, the end portions at one end of said plurality of aprons being in a first common plane, constituting a first display surface, and the opposite end portions being in a different and second plane and constituting a second display surface, and means for moving said decorated looped aprons in unison over said 70 platens to change the picture displayed in each plane display surface.

80 23. In a changeable picture apparatus, a display unit consisting of two display fronts spaced apart, a plurality of guide platens in each front and all platens in either front being parallel to each other, a plurality of looped decorated aprons each one extending over a platen in one front and over a platen in the other front, and extending between 85 the two fronts as a substantially endless belt, each display face being composed of the plurality of narrow strips consisting of the end looped portions of said aprons resting on the platens of that particular front, and means to move said aprons over said 90 platens to change the display on both fronts.

105 In testimony whereof I affix my signature.

ALEXANDER ARCHIPENKO.
